UNITED STATES PATENT OFFICE.

PRYCE W. BAILEY, OF SENECA FALLS, NEW YORK.

DESIGN FOR A MEMORIAL CROSS.

SPECIFICATION forming part of Design No. 19,471, dated December 10, 1889.

Application filed October 29, 1889. Serial No. 328,608. Term of patent 7 years.

To all whom it may concern:

Be it known that I, PRYCE W. BAILEY, a citizen of the United States, residing at Seneca Falls, in the county of Seneca and State of New York, have invented and produced a new and original Design for a Memorial Cross; and I do hereby declare the following to be a full, clear, and exact description of the same, reference being had to the accompanying drawings, forming a part thereof.

Figure 1 is a front view of my design. Fig. 2 is a similar view as it appears when in use.

The leading features of my design for a memorial cross consist in a staff A, on which there is a representation of the earth B, and on the earth is shown the end of a log or fallen oak C, upon which rests a dismounted cannon D. Above said cannon are hung a saber C and cartridge-box F, and leaning against the

staff are a musket G and the oar H. Upon said oar there is hung an anchor I. Above these implements of war is the cross J, in the center of which are the initial letters "G. A. R." Upon said cross there is a representation of an evergreen wreath of ivy K, and in the top of the vertical section of the cross there is located a vase L for the reception of flowers when decorating soldiers' graves.

What I claim is—

The design for a memorial cross herein shown and described, substantially as set forth.

In testimony whereof I affix my signature in presence of two witnesses.

PRYCE W. BAILEY.

Witnesses:

O. F. GLEASON,
C. F. KELLEY.
